UNITED STATES PATENT OFFICE.

FRED W. HOEFER, OF LYNDHURST, NEW JERSEY, ASSIGNOR TO RICHARD MEYER, OF HOBOKEN, NEW JERSEY.

BOTTLE-CLOSURE DEVICE.

1,113,119.

Specification of Letters Patent.

Patented Oct. 6, 1914.

Application filed October 4, 1912. Serial No. 723,845.

To all whom it may concern:

Be it known that I, FRED W. HOEFER, a citizen of the United States, and residing at Lyndhurst, in the county of Bergen and State of New Jersey, have invented certain new and useful Improvements in Bottle-Closure Devices, of which the following is a specification, such as will enable those skilled in the art to which it appertains to make and use the same.

This invention relates to devices for closing bottles, small jugs, jars and similar vessels, and the object thereof is to provide an improved device of this class designed for use in connection with an ordinary milk bottle or similar vessel after the ordinary stopper has been removed, and for the purposes of keeping dust and dirt out of the bottle, while the contents thereof are being discharged at different times or intervals.

The invention is fully disclosed in the following specification of which the accompanying drawing forms a part, in which the separate parts of my invention are designated by suitable reference characters in each of the views, and in which:

Figure 1 is a side view of the top of an ordinary milk bottle provided with my improved closure device;—Fig. 2 a central vertical sectional view thereof;—Fig. 3 a bottom plan view of the main part of a closure cap which I employ, and;—Fig. 4 a section on the line 4—4 of Fig. 3.

In the drawing forming part of this specification, I have shown at *a* the top or neck portion of an ordinary milk bottle, and in the practice of my invention, I provide a closure device comprising an arc-shaped spring clamping member *b*, the wings *b*² of which are adapted to be passed around the neck of the bottle below the annular enlargement *a*² at the top thereof, and as clearly shown in Figs. 1 and 2, and said member *b* is preferably stamped from sheet metal, and secured centrally of the back thereof is an upright support *c*, in the top of which is pivoted, as shown at *c*², a short lever or arm *d* the inner end of which is pivoted to a cap *f*, as shown at *d*², and the outer end of which projects to form a thumb or finger piece *d*³, and secured centrally of the part *b* and support *c*, as shown at *g* is a spring *h* which extends upwardly and is passed backwardly through a fork *c*³ at the top of the support *c*

and which bears on the bottom of the thumb or finger piece *d*³ of the lever *d*, as shown at *h*² and by depressing the outer end of the lever *d* the cap *f* may be raised into the position shown in dotted lines in Fig. 1, and the contents of the bottle, or a part thereof, may be discharged therefrom.

The cap *f* is preferably composed of a metal top disk *f*² and a bottom disk *f*³ of fibrous material which forms a packing to more securely close the top of the bottle, and the object of pivoting the lever *d* to the cap *f*, as shown at *d*³, is to permit said cap to swing freely so that it will rest evenly on the top of the neck of the bottle at all points, and completely close the same, and said cap, as will be understood, is held in a closed position by the spring *h*.

The metal disk *f*² which forms the top part of the cap *f* is provided centrally thereof with two ears *f*⁴ which are stamped from the material thereof and between which the lever *d* is pivoted, and the bottom of said metal disk *f*² is provided with barbs or prongs *f*⁵ which are stamped from the material thereof and which are preferably arranged in a circle and all of which project in the same direction, and by pressing the fibrous disk *f*³ on the bottom of the disk *f*² and turning it to the right, the said disks will be connected, as will be readily understood, and the bottom or packing disk *f*³ may be detached and a new one substituted therefor whenever desired.

My improved closure device may be used in connection with various forms of bottles or vessels and all that is necessary is to simply slide the neck of the vessel into the clamping member *b*, or slide said clamping member onto the neck of the vessel the wings *b*² of the part *b* forming spring jaws which extend sufficiently far to clamp and hold the neck of the vessel, and to secure the closure device thereto.

My improved closure device for vessels of the class specified may be made of any suitable material, and changes in and modifications of the construction described may be made, within the scope of the appended claims, without departing from the spirit of my invention or sacrificing its advantages.

Having fully described my invention, what I claim as new, and desire to secure by Letters Patent, is;

1. A closure device for vessels provided

with a neck having an annular enlargement at the top thereof, said closure device being composed of a bottom arc-shaped clamping member having spring jaws adapted to partially inclose the top part of the neck and centrally of which is secured an upright support, a lever pivoted in said support, a cap plate to the central top portion of which said lever is pivoted, and a spring secured 5 at the back of the clamping member and bearing on the under side of the outer end portion of said lever.

2. In a bottle closure, the combination of a spring clip adapted to engage the neck of 10 a bottle, a lever, means comprising a pivot

joint for connecting said lever and said clip, a stopper, a pivotal joint connecting said stopper to one arm of said lever the other arm of said lever forming a handle, and a spring tending to hold the stopper in closed 20 position.

In testimony that I claim the foregoing as my invention I have signed my name in presence of the subscribing witnesses this 3rd day of October, 1912.

FRED W. HOEFER.
